[57] **ABSTRACT**

An expandible oil collector and method for isolating oil escaping from an underwater source. The collector is in the form of a buoyant ring with an anchor ring suspended below the buoyant ring by cables. A thin, flexible wall or shield interconnects the anchor ring with the buoyant ring. When the collector is positioned over an underwater source of oil leakage, the anchor ring is lowered by means of the cables on the buoyant ring until the anchor ring rests on the underwater surface and encircles the source of leakage. The fluid collects at the surface of the water in the interior of the buoyant ring.

METHOD AND APPARATUS FOR CONFINING AND COLLECTING OIL LEAKAGE

BACKGROUND OF THE INVENTION

This invention relates to fluid recovery, and more particularly, to apparatus for isolating leakage fluid in a body of water.

A great deal of effort is being spent on producing oil from formations that are located under bodies of water. During the completion and production of wells underwater, there is a risk that substantial quantities of oil will leak from the formation through the sand into the body of water, or leakage will occur around the well head, or at some other underwater location. The loss of oil due to leakage not only represents a loss of revenue, but also causes pollution of the sea water nearby. The oil may also wash up on the shore, making the beach unsightly and causing injury to wildlife.

Efforts have been made to isolate the oil leaking from an underwater source, but typically these efforts have been directed to confining the oil at the surface, rather than preventing the stream of oil from being deflected laterally by underwater currents. If the current is strong enough or the depth great enough, the oil may be carried substantial distances from any oil recovery apparatus that is located at the surface.

Another deficiency of previously proposed apparatus for recovering or confining oil leakage is the amount of time required for installing the apparatus at the required location. Very often, leakage occurs unexpectedly and it is necessary to take action promptly before large quantities of oil are accumulated on the surface of the water.

SUMMARY OF THE INVENTION

Accordingly, it is an object of this invention to provide apparatus for isolating and confining oil leakage from an underwater source which is unaffected by underwater currents.

It is a further object of the invention to provide oil leakage recovery apparatus which may be quickly positioned over a source of leakage, and rapidly placed in operation.

A still further object of this invention is to provide oil recovery and isolation apparatus which is readily adjustable for various depths of water.

These objects are accomplished in accordance with a preferred embodiment of the invention by a buoyant ring and an anchor ring which are connected together by means of cables spaced around the circumference of the buoyant ring. The cables are connected with a hoist device for raising and lowering the anchor ring relative to the buoyant ring. A flexible sheet material is secured between the bottom of the buoyant ring and the top of the anchor ring. The sheet extends around the circumference of both rings to form a tubular shield or container. The anchor ring may be made temporarily buoyant for floating the device prior to installation over a source of leakage. The anchor ring also includes an annular channel for receiving the flexible sheet material. The channel protects the sheet material when the device is not in use.

DETAILED DESCRIPTION OF DRAWINGS

This preferred embodiment is illustrated in the accompanying drawings in which:

FIG. 1 is a schematic view, partially in cross section, of the isolation device of this invention installed over a source of oil leakage;

FIG. 2 is an enlarged cross-sectional view of the isolation device, showing the anchor partially lowered;

FIG. 3 is a top plan view of the isolation device;

FIG. 4 is a cross-sectional view, along the line 4-4 in FIG. 2, showing the anchor ring;

FIG. 5 is a cross-sectional view as in FIG. 2, but showing the anchor ring in raised position;

FIG. 6 is a cross-sectional view of a modified anchor ring in accordance with this invention; and

FIG. 7 is a cross-sectional view of a modified form of the isolation device with means for trapping gas.

DESCRIPTION OF PREFERRED EMBODIMENT

Referring to FIG. 1, the oil isolation device of 2 includes a buoyant ring 4 and an anchor ring 6. The buoyant ring 4, as shown in FIGS. 2 and 3 is in the shape of a hollow torus and the interior of the ring 4 provides sufficient buoyancy to maintain both the float ring 4 and the anchor ring 6 at water level when the anchor ring 6 is raised to the position shown in FIG. 5.

5 10 A platform 7 is supported on the float ring 4 by radial arms 8. A prime mover 10, such as a gasoline engine, is mounted on the platform 7 and is connected through a power transmission 12 to the drum of a winch 14. A plurality of cables 16 are wound on the winch 14 and extend through guides 18 over the outer perimeter of the ring 4.

15 The anchor ring 6 is also in the shape of a hollow torus and has tubular cable guides 20 spaced at uniform intervals around the circumference of the ring. These guides 20 are generally U-shaped as shown in FIG. 2. Each cable 16 passes through a 20 guide 20 and extends upwardly from the interior of the ring 6. The end of each cable 16 is secured to a bracket 22 on the interior of the float ring 4. By this arrangement, the anchor ring 6 may be raised or lowered relative to the float ring 4 by operating the winch 14 to change the length of the cables 16 25 supporting the anchor ring 6.

A tubular shield or barrier 24, which is open at opposite ends is connected at its upper end with the float ring 4. The connection is accomplished by looping the end of the shield 24 over a circular bar 26 and securing the bar 26 to the ring 4 by clamps 28. The clamps 28 are positioned at suitable intervals around the circumference of the float ring 4 on the underside of the ring 4.

The lower end of the shield 24 is attached around the circumference of the anchor ring 6 by means of a clamping ring 30, as shown in FIG. 4. The ring 30 clamps the flexible material of the shield 24 against the outer surface of the anchor ring 6. The ring 30 is held in place by screws 32 which are spaced apart along the ring 30.

35 A channel is provided on the upper side of the anchor ring 6 by a pair of concentric cylindrical walls 34 and 36 (FIG. 2). The space between the walls 34 and 36 above the ring 6 is provided for storage of the shield 24 when the anchor 6 is raised to the position shown in FIG. 5.

40 The anchor ring 6 also has a plurality of openings 38 on the lower side of the ring allowing fluid communication to the interior of the ring 6. On the upper side of the ring 6, there are filling holes 40 at spaced intervals around the ring 6. The holes 40 are tapped to receive threaded plugs 42 (FIG. 5) when the ring 6 is filled with air and the plugs 42 are applied over the openings 40, the air pressure in the interior of the ring prevents water from entering through the vent opening 38 and the ring thus provides additional buoyance for the float ring 4. When the plugs 42 are removed, however, air in the interior of the anchor ring 6 is released and the ring 6 is no longer buoyant.

45 In operation, the isolation device shown in FIGS. 1 to 5 initially has the anchor ring 6 drawn up to the position shown in FIG. 5 by means of the cables 16. The anchor ring 6 has the plugs 42 in place over the openings to trap air in the anchor ring and the shield 24 is folded into the channel which is disposed between the float ring and the anchor ring 6. When the device is positioned over a source of oil leakage which is indicated schematically at 44 in FIG. 1, the motor 10 is 50 operated to unwind the cables 16 from the winch drum, thereby lowering the anchor ring 6 sufficiently to allow removal of the plugs 42. Water then enters the interior of the anchor ring 6 through the vent openings 38. The weight of the ring 6 is supported by the cables 16. The anchor ring is lowered by means of the cables until it reaches the underwater surface indicated generally at 46 and surrounds the source 44 of the oil leakage. Of course, it is not necessary for the anchor ring 6 to rest on the surface 46, but the ring 6 should be located at a depth that is at least as great as the depth of the 55 source of oil leakage. Sufficient length of shield 24 is provided

to allow operation at various depths and the remaining, unused portion of the shield is stored within the channel between the cylindrical plates 34 and 36. The float ring 4 is supported on the surface of the water indicated at 48. The shield 24 acts as a conduit for conducting the oil to the surface at the opening in the ring 4. The flow of oil upwardly is unaffected by underwater currents because of the presence of the shield 24. The oil is accumulated on top of the water surface 48 and within the central opening in the ring 4. A layer of oil is indicated at 50 in FIG. 1. Typically, the rings 4 and 6 may be of the order of 20 to 40 feet in diameter and the rings may be stored under a drilling barge with the drill stem passing through the center of the rings 4 and 6 in order to be readily available for use, if an oil leak should develop.

A modified form of the anchor ring is illustrated in FIG. 6. The modified ring 52 is formed of a pair of generally frustoconical shells 54 and 56 which have opposed flanges 58 and 60, respectively. The lower end of the shield 24 is clamped between the flanges 58 and 60 and secured in place by bolts 62 which are spaced around the circumference of the ring 52. The support cables 16 extend through U-shaped guides 64 to avoid sharply bending the cables around the underside of the ring 52. The interior of the ring 52 forms a channel for receiving the lower end of the shield 24 when the shield is not fully extended. The ring 52 operates in the same manner as the ring 6, except that it does not have a buoyancy chamber.

Another modified form of the invention is illustrated in FIG. 7. The structure of the device is substantially the same as that illustrated in FIG. 1 and includes a float ring 4' and an anchor ring 6' which is supported by cables 16'. The shield 24' encloses the source of oil leakage 52. Gas is also being evolved at the source 52. The oil accumulates in a layer 54 on the water and above the oil layer, the gas is trapped by a canopy 56 which is secured around its perimeter to the float ring 4', the oil is pumped out of the device through a pipe 58 and a pipe 60 is connected with the canopy 56 for drawing gas from the space under the canopy. With this arrangement, both liquid and gas may be readily isolated and removed without contaminating adjacent areas.

The device of this invention can be readily transported from one location to another by floating the device on the surface of the water. Furthermore, the device can be placed in service quickly over a source of oil leakage. The shield 24 isolates the oil and gas flow from underwater currents which otherwise might divert the flow of oil away from the float ring 4. Accordingly, this device is particularly suitable for areas where substantial cross-currents are encountered.

While this invention has been illustrated and described in a preferred embodiment, with several modifications, it is recognized that variations and changes may be made therein without departing from the invention as set forth in the claims.

I claim:

1. Apparatus for confining fluid issuing from an underwater source within a flow path between the underwater source and the surface of the water, the apparatus comprising:

buoyant means capable of supporting said apparatus at the surface of a body of water, said buoyant means including a fluid barrier having a central opening therein for receiving fluid,

anchor means, said anchor means having a central opening therein,

hoist means mounted upon said buoyant means and connected to said anchor means which is capable of raising and lowering said anchor means relative to said buoyant means while said buoyant means is floating at the surface of a body of water,

conduit means having a wall of flexible material and having openings at opposite ends, means connecting one end of said conduit means with said buoyant means in alignment with said barrier opening, the opposite end of said conduit means being connected with said anchor means in alignment with said anchor opening,

whereby the opposite end of said conduit means is supported adjacent said underwater source by positioning said anchor means opening over said source and said conduit means conducts fluid issuing from said source to said fluid barrier.

2. Apparatus according to claim 1 wherein said anchor means includes adjustably buoyant means.

3. Apparatus according to claim 9 wherein said float ring includes a wall extending across said one end of said shield, said wall being supported above normal water level for trapping gas evolved from said source.

4. Apparatus according to claim 1 wherein said hoist means includes winch means mounted on said buoyant means, and cable means, said anchor means being suspended by said cable means, said winch means being operable to control the length of cable between said anchor means and said buoyant means.

5. Apparatus according to claim 1 wherein said barrier is in the shape of a ring, and said anchor means is in the shape of a ring, said barrier ring and said anchor ring being movable into coaxial and superimposed relation.

6. Apparatus according to claim 7 including channel means on said anchor ring, said channel means being in position for receiving said flexible conduit wall when said anchor ring is positioned adjacent said barrier ring.

7. Apparatus for confining fluid issuing from an underwater source within a path between the underwater source and the surface of the water, the apparatus comprising:

a float ring having sufficient buoyancy to support said apparatus at the surface of a body of water,

an anchor ring, said anchor ring having a flotation chamber therein, means for closing said flotation chamber, said anchor ring and said float ring being movable into coaxial and superimposed relation,

a tubular shield having a flexible wall and being open at opposite ends, said shield being connected at one end with said float ring and being connected at the opposite end with said anchor ring, said tubular shield being axially aligned with said rings,

said anchor ring including an annular channel having opposite sides projecting toward said float ring, said channel cooperating with said float ring to contain said shield upon movement of said anchor ring axially into engagement with said float ring, and

hoist means mounted upon said float ring and connected to said anchor ring which is capable of raising and lowering said anchor ring axially relative to said float ring while said float ring is floating at the surface of a body of water, whereby when the anchor ring is lowered relative to the float ring, the shield is progressively played out from said channel to form a continuous conduit for confining fluid from said underwater source.

8. The apparatus according to claim 7 wherein said hoist means includes a plurality of cables, each cable extending between said anchor ring and said float ring, and power winding means on said float ring for selectively changing the length of said cables between said rings.

9. The apparatus according to claim 7 wherein said flotation chamber closing means includes ports in said anchor ring, and cap means cooperating with said ports, whereby the flotation chamber may be filled with water for ballast by removing said cap means.

10. A method of confining fluid issuing from an underwater source to a flow path defined between the surface of the water, and a submerged surface adjacent and surrounding that source, the method comprising:

superimposing a floating ring over said submerged surface, said floating ring having an anchor ring adjacent thereto, cable means connected between said floating ring and said anchor ring, and a substantially compressed longitudinally extensible conduit means connected at one end to said floating ring and at the opposite end to said anchor ring, lowering said anchor ring downwardly in the water into engagement with said submerged surface by increas-

ing the length of said cable means, while maintaining said floating ring at the surface of the water and said conduit means extended between said floating ring and said anchor ring, whereby fluid issuing from the underwater source is confined to a flow path within said conduit means.

11. The method according to claim 10 wherein said anchor

ring has a buoyancy chamber therein initially filled with gas, the lowering step including flooding said chamber.

12. The method according to claim 11 wherein the lowering step includes lowering said anchor ring by said cables after said chamber flooding.
